UNITED STATES PATENT OFFICE.

PHILIP A. GEIER, OF CLEVELAND, OHIO, ASSIGNOR TO THE P. A. GEIER COMPANY, OF CLEVELAND, OHIO, A CORPORATION OF OHIO.

HANDLE-SECURING MECHANISM.

Application filed February 9, 1920. Serial No. 357,330.

To all whom it may concern:

Be it known that I, PHILIP A. GEIER, a citizen of the United States of America, residing at Cleveland, in the county of Cuyahoga and State of Ohio, have invented certain new and useful Improvements in Handle-Securing Mechanism, of which the following is a specification.

My invention relates to improvements in handle securing mechanism and has for its object the provision of means for retaining a pivoted handle member in various positions of adjustment, which equally lend themselves to the release and readjustment of such handle member.

The securing means comprise a resilient detent for holding the handle in a predetermined position and associated mechanism permitting the retention of the handle member in a plurality of working positions, as desired.

My improvements primarily are designed for use with suction cleaning appliances and I will describe the same in connection with apparatus of this character, for the purpose of setting forth the advantages and utility of the invention.

The embodiment of my improvements here set forth comprises a portable electric suction cleaner equipped with a handle member rearwardly pivoted upon its casing by means of a forked casting. One of the forked arms is associated with a sector slotted to receive a transverse securing bolt carrying a clamping thumb nut. A bowed spring member is adapted to engage the bolt head in one position and resiliently hold the fork and attached handle member in a substantially upright position. The sector preferably is integral with the bowed spring and is partially secured in place upon the casing of the suction cleaner by means of the transverse pivotal bolt. Further details may be gathered by referring to the accompanying drawings, wherein:

Fig. 1 is a perspective view partially broken away rearwardly, showing a portable suction cleaner equipped with my improvements.

Fig. 2 is a plan view of the blank as stamped out, from which the sector is formed.

Fig. 3 is a top view of the same after it has been folded upon line A—A.

Fig. 4 is an enlarged fragmentary view in

which the details of my improvements are shown; the thumb nut being used to retain the handle member in an angular position, and

Fig. 5 is a top view of the securing means in which the spring is employed to retain the handle member essentially in upright position; one of the forked arms being shown in section on line B—B, Fig. 4.

Throughout the several figures of the drawings I have employed the same character of reference to indicate similar parts.

Referring to Fig. 1, the general characteristics of a portable electric suction cleaner are shown, upon the casing A of which a handle member is rearwardly mounted. The handle member comprises the handle B shown broken away and its attaching fork C, which is pivoted to the casing by the transverse bolt D.

One arm of said fork is equipped with a securing bolt E and the thumb nut E'; the rounded head E'' of said bolt protruding beyond the slotted sector F, which latter is seated within the machined groove G, and rigidly secured therein by the pivotal bolt D. For the purpose of securing the sector directly to the casing to prevent the sector falling out of the groove G upon removal of the handle B and bolt D for any reason, a screw G' is provided which extends through the sector F into the casing.

The sector F preferably is formed integrally from the blank of Fig. 2, by folding along the line A—A. This sector has a concentric slot F' to accommodate the body of the securing bolt E and a bowed spring member F'' for engaging the head E'' of said bolt when the handle member is raised to its upright position slightly beyond the vertical, as indicated in Fig. 5.

During the use of the suction cleaner, the handle member is adjusted to any desired angular position with respect to the casing, such as will suit the user. By tightening the thumb nut E', this angular position of said handle member will be retained indefinitely, since it is rigidly clamped to the sector F and thereby held in operative position with the casing, as indicated in Figs. 1 and 4. However, the handle member may be released merely by loosening the thumb nut, whenever it is desired to change its angular position or put away the suction cleaner.

Thus, whenever the apparatus is to be stored during non-use, or when it is left standing in the room, it is desirable to elevate the handle member out of the way into substantially vertical position, wherein it will be held merely by engaging the bolt head E'' with its coacting spring F'', as indicated in Fig. 5. However, the handle may readily and instantly be released from this position merely by depressing it to the desired angle for operating the suction cleaner. Of course, the fork may be left entirely unsecured by the bolt E when desired, so that it will be freely movable about its pivot bolt D.

Having now described the features of my invention and the preferred use and advantages thereby obtained, I claim as new and desire to secure by Letters Patent, the following:

1. The combination with a handle member, of a casing, an arcuate stop device secured to said casing, pivotal means for securing said stop device, clamping means for retaining the handle member in any desired position upon said arcuate stop device, and spring means adapted to directly coact with the before mentioned clamping means whereby said handle member may be temporarily and resiliently held in a given position.
2. The combination with a pivoted handle member, of a casing having a receiving groove, an arcuate stop device seated within said groove, a pivot mounting said handle member and rigidly centering and securing the stop device, clamping means for retaining the handle in adjusted position upon the arc as desired, a thumb nut controlling the same, and resilient means forming a part of said stop device and adapted to cooperate with said clamping means whereby the handle member may be resiliently retained in a different position, substantially as set forth.
3. The combination with a pivoted handle

member, of a fixedly mounted integral stop-device associated therewith and comprising an arcuate portion and a laterally extending spring part adapted temporarily to engage and hold the pivoted handle member in a given position, substantially as set forth. 50

4. The combination with a pivoted fork for a handle or the like, of an associated stop-device rigidly mounted with respect thereto, means for clamping the fork in adjusted position thereon, and resilient means for temporarily holding said fork in a given position, substantially as set forth. 55

5. An integral stop-member formed from a single punching, comprising a body having an arcuate slot near one end and a spring portion extending freely from the opposite end of the body in position to be bent in overlying relation with respect to said slot, substantially as set forth. 60

6. The combination with a frame member, of a pivoted handle therefor, an integral stop-member comprising a body having an arcuate slot and a spring detent portion overlying said slot, means for securing said stop-member to the casing, an engaging detent upon the handle traveling in the arcuate slot in position to be held by the spring detent and means for rigidly clamping the pivoted handle in various positions of adjustment upon the stop-member, substantially as set forth. 70

7. The combination with a casing, of a pivoted handle therefor, an arcuate stop-member, secured within a groove in said casing, a pivot mounting the handle and rigidly centering the stop-member upon the casing, and clamping means associated with the pivoted handle, adapted to secure it in various positions of adjustment with respect to the stop-member, substantially as set forth. 80

In testimony whereof I do now affix my signature.

PHILIP A. GEIER.
